CARBURETER.

1,116,325.

Specification of Letters Patent.

Patented Nov. 3, 1914.

Application filed July 7, 1913. Serial No. 777,686.

To all whom it may concern:

Be it known that I, GEORGE PONAROUSE, a citizen of the United States, residing in the city and county of San Francisco and State 5 of California, have invented new and useful Improvements in Carbureters, of which the following is a specification.

This invention relates to a carbureter especially constructed for volatilizing hydro- 10 carbon liquids and mixing same with air, for lighting and fuel purposes.

The object of the present invention is to provide a simple, cheaply-manufactured, easily-operated carbureter which is compact 15 in construction and automatic in operation.

Another object of the invention is to provide means for automatically admitting air to the carbureter.

Another object is to provide means within 20 the carbureting chamber which will prevent any unvaporized fuel from escaping through the gas outlet pipe.

Further objects will appear hereinafter.

The invention consists of the parts and 25 the construction and combination of parts as hereinafter more fully described and claimed, having reference to the accompanying drawings, in which—

Figure 1 is a vertical section of the apparatus. Fig. 2 is a section on the line X—X of Fig. 1.

Referring to the drawings: A indicates a carbureting chamber which is closed by a bell 2 of suitable construction, vertically 30 movable and mounted in the water-seal 3, formed by a jacket 4, inclosing the carbureting chamber. The lower end of the carbureting chamber is provided with a sloping bottom 5, and is connected at its lowest point 35 with an air inlet pipe 7, which in turn is connected with a rotary blower or fan 8, mounted on a platform 9, supported, as at 40 10, a suitable distance above the gas container.

Slidably mounted upon a gas outlet pipe 45 11, extending into the carbureting chamber, is a funnel-shaped member 12, having an inclined annular trough 13 formed on its inner surface, and operable in connection 50 with the funnel-shaped member 12 is a spray nozzle 14, suitably secured, as at 15, upon the end of the air inlet pipe 7. 16 indicates a fuel supply pipe, which is also con-

nected with the bottom of the carbureting chamber, as indicated at 17, and suitably 55 connected with same, for the purpose of controlling the fuel level within the carbureting chamber, is a float 18, connected with a lever 19, pivotally mounted, as at 20, and having upon its outer end a needle valve 21 60 which will automatically close the flow of entering fuel when a predetermined level has been reached. The fuel supply pipe 16 is further supplied with an automatically-operated cut-off valve 22, the operation of 65 which will be later described. The rotary blower or fan 8 may be driven from any suitable source, but preferably an electric motor, indicated at 23, which in turn is connected with a storage battery 24. 70

Suitably mounted, as at 25, is a knife-switch 26, which is provided for the purpose of making or breaking the electric circuit to the motor. For the purpose of automatically shutting off the air and fuel supply to the carbureting chamber when the floating bell 2 has become charged, the following automatic switching mechanism has been provided.

Connected, as at 27, to the top of the bell 80 2, is a flexible cord 28 which extends in an upward direction and passes over a pulley 29, secured to the platform. From here the flexible cord extends in a downward direction and is secured, as at 30, to a wedge-shaped weight 31, slidably mounted in a suitable frame, or as here shown on the jacket; and attached to the weight 31, as at 32, is another flexible cord 33, to the lower end of which is secured a ball-shaped weight 90 34. Similarly secured on the opposite side of the bell, as at 35, is another flexible cord 36, which passes over a direction pulley 37, and which is also secured to a wedge-shaped weight 31^a; and similarly secured, as at 32^a, 95 is a flexible cord 33^a, carrying a weight 34^a; and suitably secured to the opposite sides of the jacket in the path of the sliding weights 31—31^a, as at 38, is a pair of bracket members 39—39^a, the upper surfaces of which 100 are sufficiently inclined to retain the weights 34 and 34^a when these have been deposited upon the top of the brackets; and by referring to the cross-section shown in Fig. 2, it will be seen that the top surfaces 105 of the brackets are slightly concave in cross-

section to prevent the weights from rolling off the sides of the shelf when once deposited thereon.

By referring to Fig. 1 in the drawings it will be seen that a continuous, flexible cord 40 is secured to the weights 34-34^a. The ends of the cord 40 are extended in an upward direction on either side and pass over guide pulleys 41 and 42; and secured to the cord 40, between the guide pulleys 41 and 42 and the knife-switch 26, which is also secured to the cord 40, is a lever 43, pivotally mounted upon the blower 8, as at 44. The lower end of the lever is provided with a valve or disk 45 which is so positioned that it may be thrown into or out of register with the air inlet 46 of the blower.

Extending from the top of the bell 2 is a bracket 47, to which is secured a rod 48, suitably guided and slideable in outwardly-extending brackets 49. The lower end of the rod 48 is so positioned as to contact with a lever 50, secured upon the stem of the cut-off valve 22; and attached to the rod, as at 51, is another flexible cord 52, the other end of which is secured to the lever 50.

The operation of the apparatus will be as follows: Referring to Fig. 1 of the drawings it will be seen that the knife-switch 26 is placed in such a position as to close the circuit between the battery and the motor 23; the motor being direct connected to the blower will cause a continuous discharge of air through the pipe 7 and nozzle 14. The cut-off valve 22 is also shown in its open position, and will thus permit an inflow of gasolene or similar volatile fuel into the interior of the carbureting chamber. A certain amount of volatile fuel is thus constantly flowing into the nozzle 14, through the openings 14^a and will consequently be projected or sprayed in an upward direction, as indicated in the drawing; the air having sufficient velocity and pressure to cause this spray action. The upwardly-projecting spray of fuel and air causes the volatile fuel to be partly evaporated, and evaporation is further assisted by spreading the fuel in a thin film on the outer end and inner face of the conical member 12; the velocity of the incoming air being sufficient to carry the spray above the upper edge of the conical member will thus permit a certain amount of spray to lodge on the inner face of the conical member, where further evaporation is permitted. A large surface is thus provided which produces a perfect evaporation of the fuel and any unvaporized fuel running down the inside surface of the funnel is prevented from entering through the discharge pipe 11, by being collected in the annular trough 13, formed near the lower end of the conical member. An opening 13^a is provided at the lowest point of the trough to permit such unvaporized fuel

to be discharged back into the bottom of the carbureting chamber, where it is again projected in an upward direction by the velocity of the inflowing air discharging through the nozzle 14.

A constant level of fuel in the bottom of the chamber is always maintained by the float 18, which automatically closes the fuel inlet the moment a predetermined fuel level has been reached.

The out-flow discharging through the pipe 11 may be used for lighting or fuel purposes, as the case may be; and it will also be understood that the volume of gas consumed will vary according to the number of lights, or the amount of fuel used.

For the purpose of automatically shutting-off the fuel and air supply to the carbureting chamber when the chamber has been completely charged, which takes place when the bell 2 has risen to a predetermined height, the automatic switching mechanism previously described has been provided. The operation of this part of the mechanism will be as follows: The moment the bell 2 has risen to a certain point with relation to the carbureting chamber A and the surrounding frame 10, it will be seen that the wedge 31 will be lowered into a position where it will force the weight 34 off the supporting shelf 39. The falling of the weight 34 off the shelf will cause a sufficient jerk upon the cord 40 to throw the knife-switch 26,—this being sudden so as not to blow out the fuse of the motor—into the dotted line position shown, thus breaking the circuit to the motor and stopping the operation of the blower. The movement of the cord 40 will also rock the arm 43 into the dotted line position shown, where the valve 45 will close the intake opening 46 on the blower; the valve 45 being provided for the purpose of preventing any escape of vapor through the pipe 7 and blower 8. The upward movement of the bell 2 to its upper position, which caused the release of the weight 34, is also transmitted through the cords 36 and 33^a to raise the weight 34^a to its supporting shelf 39^a, which is indicated by dotted lines; the depositing of the weight 34^a upon the bracket 39^a being accomplished just previous to the release of the weight 34 on the opposite side, which release caused the opening of the electric circuit, etc. The upward movement of the bell 2 is further transmitted through the extending arm 47 and rod 48 to tighten the cord 52 and pull the arm 50 up, which closes the valve and consequently shuts off the fuel supply to the carbureting chamber. The volatile fuel contained in the bottom of the chamber will thus be permitted to flow back through the nozzle 14 into the lower bend of the air inlet pipe 7, and will thus act as a trap, which, in conjunction

with the valve 45, will prevent any back-flow of gas from the container. It will thus be seen that the provision of the valve 45, in connection with the trap provided in the 5 lower end of the inlet pipe, will positively prevent any back-flow of gas through the pipe 7. A continued consumption of gas from the container will naturally cause the bell to lower as the supply within the chamber diminishes; and will, when a predetermined 10 low level has been attained, lower the weight 31^a into a position where it will release the weight 34^a previously deposited on the shelf 39^a when the bell assumed its 15 upper position; the weight 34^a being released at this point will fall into the full line position, indicated at 34^a, and cause the cord to move in the direction indicated by arrow α , which will throw the knife-switch 26 back into normal position and close the circuit to the motor, which will immediately be transmitted to operate the blower. The lever 43, secured to the cord, 20 will also be thrown into the position indicated in Fig. 1, and will again permit air to enter the blower through the intake opening 46. The air pressure caused by the blower will consequently force the fuel out of the trap end of the pipe 7 and cause it to 25 be thrown in an upward direction against the conical member and volatilized upon the surface of same and further caused to be mixed with the incoming air. The lowering of the bell 2 will also cause the weight 34 to 30 be raised up and deposited upon the shelf 39 just previous to the release of the weight 34^a on the opposite side, which caused the electric circuit to be closed, etc.; and the similar downward movement of the bell 2 35 is also transmitted, through the arm 47 and rod 48, to depress the lever 50 into the position shown in Fig. 1, where fuel is again admitted to enter the carbureting chamber. The cycle of operation will thus be continued 40 until the container becomes fully charged, when the automatic switching mechanism will again be actuated by the rise of the bell, as previously described. By providing a slidably-mounted, conical 45 member 12 it becomes possible to raise or lower this with relation to the discharge pipe 11 into such a position that a highly combustible mixture may always be secured, and any unvaporized fuel entering the upper 50 end of the conical member 12 is prevented from entering the discharge by being collected and drained off by the inclined trough indicated at 13. A perfect, highly-combustible mixture is thus secured, which is 55 automatically formed from time to time as the gas is consumed.

By providing a carbureter constructed as here shown, it becomes possible to use low-grade fuels; any so-called fuel residue being 60 prevented from collecting in the bottom of

the carbureting chamber, as the float 18 will only permit a certain fuel level within the chamber. The lower volatile grades of fuel which might have a tendency to collect in the chamber are constantly circulated, 70 agitated and projected against the vaporizing surfaces of the conical member, and will thus finally be caused to vaporize, together with the more volatile product admitted to the carbureting chamber. Collection of 75 residue within the chamber is thus positively prevented, and a lower grade of fuel than heretofore generally used may be handled with a consequent low cost of operation to the consumer. 80

The apparatus here shown is simple, compact and automatic in operation, and takes less space than any machine of similar capacity heretofore constructed.

The material and finish of the several 85 parts of the apparatus are such as experience and judgment of the manufacturer may dictate.

Having thus described my invention, what I claim and desire to secure by Letters Patent, 90 is:

1. A carbureter comprising in combination, a gas generating chamber, a water-sealed movable bell inclosing said chamber, an outlet pipe connected with said chamber, 95 a conically shaped vaporizing member adjustably mounted on said pipe, means for projecting air and volatile fuel in a spray against said surface, and means automatically controlled by the bell for opening or 100 closing the air and fuel supply.

2. A carbureter comprising in combination, a gas-generating chamber, a water-sealed movable bell inclosing said chamber, an outlet pipe connected with said chamber, 105 a conical-shaped vaporizing member adjustably mounted on said pipe, an annular trough formed on the inner surface of the conical-shaped member having a discharge opening, means for projecting air and volatile fuel in a spray against said surface, and means automatically actuated by the bell for opening or closing the air and fuel 110 supply.

3. A carbureter comprising in combination, a gas-generating chamber, a water-sealed movable bell inclosing said chamber, an outlet pipe connected with said chamber, a conically shaped vaporizing member adjustably mounted on said pipe, a pipe connected at one end with a source of air supply and at the other end with the bottom of the chamber, a trap formed in the lower end of the pipe, a spray nozzle on the lower end of the air pipe within the chamber, a 120 fuel supply pipe connected with the chamber, and means for controlling the admission of fuel to maintain a constant fuel level within the chamber with relation to the spray nozzle. 125

4. A carbureter comprising in combination, a gas generating chamber, a water-sealed movable bell inclosing said chamber, an outlet pipe connected with said chamber, 5 a conically shaped vaporizing member adjustably mounted on said pipe, a pipe connected at one end with a source of air supply and at the other end with the bottom of the chamber, a trap formed in the lower 10 end of the pipe, a fuel supply pipe connected with the chamber, means for controlling the admission of fuel to maintain a constant fuel level within the chamber, a pipe within the chamber connected with the air pipe, 15 said pipe projecting above the fuel level, and a series of perforations formed in the lower end of said pipe.

5. A carbureter comprising in combination, a gas generating chamber, a water-sealed 20 movable bell inclosing said chamber, an outlet pipe connected with said chamber, a conically shaped vaporizing member adjustably mounted on said pipe, a pipe connected at one end with a source of air supply, and 25 at the other end with the bottom of the chamber, a trap formed in the lower end of the pipe, a spray nozzle on the lower end of the air pipe within the chamber, a fuel supply pipe connected with the chamber, means 30 for controlling the admission of fuel to

maintain a constant fuel level within the chamber with relation to the spray nozzle, and means actuated by the bell for opening or closing the air supply.

6. A carbureter comprising in combination, a gas generating chamber, a water-sealed movable bell inclosing said chamber, an outlet pipe connected with said chamber, a conically shaped vaporizing member adjustably mounted on said pipe, a pipe connected at one end with a source of air supply, and at the other end with the bottom of the chamber, a trap formed in the lower 35 end of the pipe, a fuel supply pipe connected with the chamber, means for controlling the admission of fuel to maintain a constant fuel level within the chamber, a pipe within the chamber connected with the air pipe, 40 said pipe projecting above the fuel level, a series of perforations formed in the lower 45 end of said pipe, and means actuated by the bell for opening or closing the air supply.

In testimony whereof I have hereunto set my hand in the presence of two subscribing witnesses.

GEORGE PONAROUSE.
